UNITED STATES PATENT OFFICE.

JOHN L. OEFINGER, OF CHICAGO, ILLINOIS.

TOOL FOR CUTTING OFF GAS-PIPE OUTLETS.

SPECIFICATION forming part of Letters Patent No. 595,727, dated December 21, 1897.

Application filed August 19, 1897. Serial No. 648,808. (No model.)

To all whom it may concern:

Be it known that I, JOHN L. OEFINGER, a citizen of the United States, residing at Chicago, in the county of Cook and State of Illinois, have invented certain new and useful

5 Improvements in Tools for Cutting Off Gas-Pipe Outlets; and I do hereby declare the following to be a full, clear, and exact description of the invention, such as will enable 10 others skilled in the art to which it appertains to make and use the same.

My invention has for its object to provide 15 a pipe-cutter adapted for general use and especially adapted for cutting off gas-pipe outlets close to the walls. It is of course well understood that in building houses the gas-pipe outlets are ordinarily left to project anywhere from two to six inches, and, on the other hand, that it is desirable that these outlets should be as short as possible, especially 20 when combination or electric fixtures are to be applied, as if the outlets are long it becomes necessary to use very deep canopies to cover the insulating-joints. So far as I am aware 25 none of the various pipe-cutters now in use will cut close enough to the wall to leave only such length of pipe as will be just sufficient to attach thereto a cap or fixture. Heretofore when it has been desired to cut off gas- 30 pipe outlets close to the wall it has been necessary to resort to the use of a hack-saw, which is quite inconvenient and is, moreover, likely to disfigure the wall quite seriously. 35 With my novel tool an outlet can be cut off within three-eighths of an inch of the wall and left in perfect condition to be threaded in the usual manner for the purpose of hanging the fixtures.

In order that others may be enabled to 40 understand the construction and operation of my novel tool, I will proceed to describe the same, referring by numbers and letters to the accompanying drawings, forming part of this specification, in which—

45 Figure 1 is a side elevation illustrating my novel tool in use; Fig. 2, a front elevation corresponding thereto; Fig. 3, a central horizontal section, and Fig. 4 is a rear elevation.

A denotes the body of my novel tool, which 50 is shown as provided with internally-threaded hubs 1 to receive operating-handles 2, with pairs of lugs 3 and with a central sleeve 4,

which receives the end of the gas-pipe outlet to be cut off. In practice the body, the pairs of lugs, and the central sleeve are cast in a 55 single piece, and the rear portion of the sleeve is externally threaded, as at 5.

6 denotes levers pivoted between the pairs of lugs, the rear ends of said levers extending backward within the body and the forward ends thereof being provided with rotary cutters 7.

8 denotes a cone which is internally threaded to engage the thread on the sleeve and is shown as provided on its base with hand-pieces 9 for convenience in operation. The action of the cone will be clearly understood from Figs. 3 and 4.

In use the operator turns the cone outward on the sleeve, which permits the inner ends 70 of the levers to swing inward, and consequently throws the outer ends carrying the cutters outward. The tool is then placed over the gas-pipe outlet to be cut, the outlet passing between the cutters into the sleeve, 75 as clearly shown in Fig. 3. The operator then turns the cone inward on the sleeve, throwing the inner ends of the levers outward and the outer ends, which carry the cutters, inward and causing the cutters to 80 engage the pipe to be cut off. The operator then by means of the operating-handles turns the tool upon the pipe, setting the cutters inward, if required, by means of the cone until the end is cut off. 85

Having thus described my invention, I claim—

1. A tool of the character described comprising a body having a central opening or passage for the pipe to be cut off and an externally-threaded sleeve, levers pivoted to the body and carrying at their outer ends cutting-off tools adapted to engage the pipe, and a cone threaded to engage the sleeve and adapted to tilt the levers and move the cutters toward each other in operation. 90

2. A tool for cutting off gas-pipe outlets, comprising a body having a central opening or passage for the pipe to be cut off, and having lugs and an externally-threaded sleeve, 100 levers pivoted to the lugs and carrying cutting-off tools at their forward ends and a cone threaded to engage the sleeve and adapted to be rotated thereon whereby the levers are

tilted and the cutters moved inward in contact with the pipe.

3. A tool of the character described comprising a body, lugs, and a central sleeve formed in a single piece and having a central passage from end to end, levers pivoted to the lugs and carrying cutting-off tools at their forward ends and a cone for engaging the levers and threaded to engage the sleeve sub-

stantially as described, for the purpose set forth.

In testimony whereof I affix my signature in presence of two witnesses.

JOHN L. OEFINGER.
